UNITED STATES PATENT OFFICE.

ALEKSANDER PLUDOWSKI, OF WATERBURY, CONNECTICUT, ASSIGNOR OF ONE-FOURTH
TO WINCENTY WODZINSKI AND ONE-HALF TO BRONISLAUS GREBZISZEWSKI, BOTH
OF WATERBURY, CONNECTICUT.

LAMP-EXTINGUISHER.

1,211,226.

Specification of Letters Patent.

Patented Jan. 2, 1917.

Application filed July 28, 1916. Serial No. 111,859.

To all whom it may concern:

Be it known that I, ALEKSANDER PLUDOWSKI, a subject of the Czar of Russia, residing at Waterbury, in the county of New Haven and State of Connecticut, have invented certain new and useful Improvements in Lamp-Extinguishers, of which the following is a specification.

This invention relates to certain new and useful improvements in lamp extinguishers.

The primary object of the invention is the provision of a pneumatic device adapted for extinguishing the light in an ordinary lamp without the necessity of bringing the hand 15 of the operator near the chimney of the lamp.

A further object of the invention is the provision of a ready extinguisher for lamps formed as a part thereof when the lamp is manufactured, the same being readily operable whenever desired for use.

A still further object is to provide a compressed air tank in connection with a lamp whereby an air blast controllable for extinguishing the lamp is operatively arranged.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is a side elevation of a lamp provided with the present device partially shown in vertical section. Fig. 2 is a transverse sectional view taken upon line II—II of Fig. 1. Fig. 3 is a front view of the air blast nozzle, and, Fig. 4 is a transverse sectional view thereof.

The present invention broadly consisting 45 in the provision of an extinguisher for lamps, the same is herein illustrated in connection with a kerosene lamp 10 of substantially the usual construction having an oil reservoir 11 with a burner 12 mounted thereon, the latter being provided with a glass chimney 13 while a base 14 is provided for supporting the reservoir 11 by means of a pedestal 15.

It will be understood that the reservoir

supporting pedestal and base may be integrally formed of glass or metal as found desirable, an axial bore 16 being herein provided in the pedestal 15 communicating with the chamber 17 in the base 14. A communicating pipe 18 extends through the reservoir 11 from the bore 16 to a point in the top of the reservoir 11 adjacent the burner 12, a threaded bushing 19 being provided in the upper end of the said pipe.

A tubular casing 20 is fitted within the bore 16 having a closure cap 21 threaded upon its lower free end within the base chamber 17. A central partition 22 is arranged in the casing 20 having a flap valve 23 upon its inner face adapted for normally closing a valve opening 24 centrally arranged in the said partition.

An air compressing piston 25 is tightly fitted for reciprocating in the lower portion of the casing 20 having an operating rod 26 attached thereto, the said rod extending axially of the said casing being slidably arranged through a stuffing box 27 centrally carried by the casing cap 21. An air inlet port 28 is provided in the cap 21, it being understood that the piston 25 is valved in the usual manner so that the vertical reciprocations thereof by means of the rod 26 pumps air through the inlet 28 into the casing 20 and thence through the partition 24 into the upper portion of the casing 20. A handle 29 is arranged upon the outer end of the piston 26 while the latter has a hinge joint 30 allowing the piston rod to be angularly bent and the free portion thereof to be engaged over a hook 31 in the base chamber 17, as illustrated by dotted lines in Fig. 1 of the drawing.

Spaced plates 32 are arranged adjacent the upper end of the casing 20 having aligning valve openings 33 therein while a slide valve 34 closely fits between the said plates having a port 35 extending therethrough normally maintained out of alignment with the valve openings 33 by means of a spring 36. The valve 34 is provided with a stem 37 projecting outwardly of the pedestal 15 arranged with a finger piece 38 thereon whereby the valve may be forced inwardly against the action of the spring 36 for bringing the port 35 thereof into alignment with openings 33, thereby allowing the compressed air within the casing 20 to pass into

the small chamber portion 39 in the upper end of the said casing so that the air may freely pass through the pipe 18. A fan-shaped nozzle 40 is screw-threaded by means of a nipple 41 into the bushing 19, a plurality of outlet perforations 42 being arranged in the face of the said nozzle adjacent the burner 12 in an inclined position beneath the horizontal air inlet plate 43 of the burner.

10 In the operation of the device it will be understood that a piston 25 will be actuated from time to time for the purpose of maintaining a supply of air under compression 15 within the casing 20 between the partition 22 and the plates 32. When designed to extinguish the light of the burner 12, the flame of which is herein illustrated at 44, the finger piece 38 will be depressed thereby 20 sliding the valve 34 to its open operative position, allowing the compressed air to flow through the pipe 18 and the nozzle 40. The air will thus be forced through the perforations 42 of the nozzle and will pass 25 through the air receiving plate 43 of the burner, providing a draft for extinguishing the blaze 44 by blowing out the same. A device is thus provided upon a lamp which is ready for immediate use in extinguishing 30 the light and is readily operable by the hand when grasping the lamp supporting pedestal 15 and without the necessity of bringing any part of the body near the lamp chimney 13, it being intended to prevent 35 the accidental burning of the operator during the extinguishing of the lamp.

What I claim as new is:—

1. A lamp comprising a reservoir, a supporting pedestal having an axial bore, a casing within the said bore, a communicating pipe between the upper end of the said casing extending through the said reservoir and having its upper end adjacent the burner of the lamp, a fan-shaped outlet 45 nozzle in the upper end of the said pipe having perforations directed toward the burner of the lamp, a compressed air chamber within the said casing, and a normally closed controlling valve adjacent the upper 50 end of the said casing operable exteriorly of one side of the said pedestal.

2. A lamp comprising a reservoir, a supporting pedestal having an axial bore, a casing within the said bore, a communicating pipe between the upper end of the said casing extending through the said reservoir and having its upper end adjacent the burner of the lamp, a fan-shaped outlet nozzle in the upper end of the said pipe 55 having perforations directed toward the burner of the lamp, a compressed air chamber within the said casing, a normally closed controlling valve adjacent the upper end 60 of the said casing operable exteriorly of one side of the said pedestal, a supporting

base for the said pedestal having a chamber therein, a perforated cap upon the lower end of the said casing within the said base chamber, and an air compressing piston within the lower end of the said casing 70 provided with an operating handle normally arranged within the said base chamber.

3. A device of the class described comprising in combination with a lamp having an oil reservoir, a burner upon the said reservoir, and a pedestal provided with a supporting base attached beneath the latter, the said burner having a perforated air receiving plate adjacent the bottom thereof 75 adjacent the burning portion of the wick of the lamp, the said pedestal being provided with an axial bore and said base with a chamber communicating with the said bore, a casing arranged within the said bore, 80 a closure cap for the said casing within the said base chamber, a pipe extending through the said reservoir and communicating with the said casing at the upper end thereof, a fan-shaped nozzle arranged in the upper 85 end of the said pipe beneath the said plate and having outlet openings directed toward the said plates, a controlling valve within the said casing adjacent the said pipe, and an air compressing means for the said cas- 90 ing. 95

4. A device of the class described comprising in combination with a lamp having an oil reservoir, a burner upon the said reservoir, and a pedestal provided with a supporting base attached beneath the latter, the said burner having a perforated air receiving plate adjacent the bottom thereof 100 adjacent the burning portion of the wick of the lamp, the said pedestal being provided with an axial bore and said base with a chamber communicating with the said bore, a casing arranged within the said bore, 105 a closure cap for the said casing within the said base chamber, a pipe extending through the said reservoir and communicating with the said casing at the upper end thereof, a fan-shaped nozzle arranged in the upper 110 end of the said pipe beneath the said plate and having outlet openings directed toward the said plate, spaced plates within the said 115 casing adjacent the upper end thereof providing a reduced chamber portion adjacent the communicating end of the said pipe, the said plates being provided with alining openings therethrough, a normally closed spring-pressed slide valve between the said plates having a port therethrough, an operating finger piece for the said slide valve arranged adjacent the upper end of the said pedestal 120 exteriorly thereof, and an air compressing means in the lower end of the said casing. 125

5. A device of the class described comprising in combination with a lamp having an oil reservoir, a burner upon the said res- 130

ervoir, and a pedestal provided with a supporting base attached beneath the latter, the said burner having a perforated air receiving plate adjacent the bottom thereof 5 adjacent the burning portion of the wick of the lamp, the said pedestal being provided with an axial bore and said base with a chamber communicating with the said bore, a casing arranged within the said bore, a 10 closure cap for the said casing within the said base chamber, a pipe extending through the said reservoir and communicating with the said casing at the upper end thereof, a fan-shaped nozzle arranged in the upper 15 end of the said pipe beneath the said plate and having outlet openings directed toward the said plate, spaced plates within the said casing adjacent the upper end thereof providing a reduced chamber portion adjacent 20 the communicating end of the said pipe, the said plates being provided with alining open-
ings therethrough, a normally closed spring-pressed slide valve between the said plates having a port therethrough, an operating finger piece for the said slide valve arranged 25 adjacent the upper end of the said pedestal exteriorly thereof, a partition within the said casing substantially centrally thereof having a valved port therethrough, an air compressing piston within the said casing 30 beneath the said partition, a two-part operating stem for the said piston, a closure cap for the said casing within the said base chamber through which the said stem is slidably arranged, and a supporting means 35 within the said base for the upper pivoted end portion of the said stem when the device is inoperatively positioned.

In testimony whereof I affix my signature.

ALEKSANDER PLUDOWSKI.
